UNITED STATES PATENT OFFICE

170,515

WALL PLAQUE

Fred W. White, Cheboygan, Mich.

Application May 29, 1953, Serial No. 25,241

Term of patent 7 years

(Cl. D29—23)

To all whom it may concern:

Be it known that I, Fred W. White, a citizen of the United States, residing at Cheboygan, in the county of Cheboygan and State of Michigan, have invented a new, original, and ornamental Design for a Wall Plaque, of which the following is a specification, reference being had to the accompanying drawing, forming a part hereof.

I claim:

The ornamental design for a wall plaque, as shown.

FRED W. WHITE.
